United States Patent Office.

WISNER H. TOWNSEND, OF NEW YORK, N. Y.

Design No. 3,970, dated April 12, 1870.

DESIGN FOR AN OIL-CLOTH PATTERN.

The Schedule referred to in these Letters Patent and making part of the same

To all whom it may concern:

Be it known that I, WISNER H. TOWNSEND, of the city of New York, in the county and State of New York, have invented a new and original Design for Oil-Cloths; and I do hereby declare that the following is a full, clear, and exact description thereof, which will enable others skilled in the art to make and use the same, reference being had to the accompanying drawing forming part of this specification.

This invention relates to a new design for oil-cloths, the same being entirely composed of ornamental squares, of which some are divided into triangles.

The accompanying drawing represents my design.

The same is mainly composed of five squares, A, B, C, D, and E, all of equal size, the four last-named squares surrounding the square A, as shown.

The square A is, by means of two lines *a a* which bisect its sides, divided into four smaller squares *b b*, and each of the latter is, by a diagonal, *c*, divided into two triangles, of which the outer one, *d*, forms a corner of the main square A, while the four inner triangles, *e e*, together constitute a square within A, and half as large as the same.

The outer triangles *d* are ornamented, each by a central rosette, *f*, and by arabesques *g g* surrounding the same.

Each of the triangles *e* is plainly ornamented by trefoil, *h*, as shown.

Two squares B D, which are on the opposite sides of the square A, are subdivided by lines *a* and *c*, in the same manner in which the square A is subdivided. The several triangles in them, however, are only ornamented by trefoils, as shown.

Each of the remaining squares C E is ornamented by a central rosette, *h*, which is contained within central figure, *i*, which is a square with rounded-outward projecting corners.

The figure *i* contains arabesques *j* in the corner and is also surrounded by two circles *k k* and arabesques *l*, as shown.

The drawing represents two full squares A A, with one half square E and a half square D between them and with two quarters of squares C and two of square B at the corners.

The colors of the several squares, triangles, and figures may be varied at will.

I claim as my invention—

The design for an oil-cloth, as shown.

WISNER H. TOWNSEND.
